UNITED STATES PATENT OFFICE.

WILLARD F. RICHARDS, OF BUFFALO, AND WILLIAM A. TURBAYNE, OF LANCASTER, NEW YORK, ASSIGNEES, BY MESNE ASSIGNMENTS, TO GOULD COUPLER COMPANY, OF NEW YORK, N. Y.

ELECTRIC-LIGHTING APPARATUS FOR RAILWAY-CARS.

SPECIFICATION forming part of Letters Patent No. 784,071, dated March 7, 1905.

Application filed April 9, 1904. Serial No. 202,373.

To all whom it may concern:

Be it known that we, WILLARD F. RICHARDS, residing at Buffalo, and WILLIAM A. TURBAYNE, residing at Lancaster, in the county of Erie and State of New York, citizens of the United States, have invented new and useful Improvements in Electric-Lighting Apparatus for Railway-Cars, of which the following is a specification.

- 10 This invention relates to apparatus employed in electric systems of distribution, such as the car-lighting and power system disclosed in United States Letters Patent of William A. Turbayne, No. 757,695, dated April 19, 1904, and more particularly to a supporting-frame for a portion of the apparatus including a dynamo, the motor which drives the same, and a switch which is operated by the motor.
- 15 The object of the invention is to provide a containing frame of simple, strong, and desirable construction for supporting said several devices in a compact convenient relation and which enables the ready assembling 20 of the parts for installing the apparatus and detachment thereof for making repairs and replacing worn parts.

In the accompanying drawings, consisting of two sheets, Figure 1 is a vertical sectional elevation of an apparatus having a frame embodying the invention. Fig. 2 is a plan view thereof, partly in section. Fig. 3 is a view thereof, one-half in end elevation and one-half in vertical section, omitting the 35 switch. Fig. 4 is a sectional elevation, on an enlarged scale, in line 4-4, Fig. 1, of one of the bearing-standards. Fig. 5 is a fragmentary section, on an enlarged scale, of one of the armature-shaft bearings, showing the 40 cap detached. Fig. 6 is a section of the bearing-standard shown in Fig. 4, the worm-wheel being removed.

Like letters of reference refer to like parts in the several figures.

45 A represents a base or stand which is preferably in the form of a hollow casting of generally-rectangular shape, having a substantially flat upper face on which the dynamo

B and motor B' for driving the same are supported. The armatures C C' of the dynamo 50 and motor are secured upon a common armature-shaft D, the end portions of which are journaled in bearing-standards E E'. The latter are bolted to the base A (see Fig. 3) and are preferably in the form of hollow 55 housings and are provided with tops or caps e, which are bolted or otherwise removably secured to the standards.

F represents bearing-sleeves or bushings for the armature-shaft, one supported in 60 each of the hollow bearing-standards in a saddle-block or cross-piece f of the hollow bearing-standard, in which it is retained by a cross piece or bar f" on the removable cap of the standard, having a semicircular seat 65 to surround the upper portion of the bearing-sleeve or bushing. The bearing-sleeves or bushings, mounted as described, provide self-aligning bearings for the armature-shaft.

The dynamo and motor are of that kind 70 having laminated field-magnets composed of parallel thin metal plates g, bound or clamped together.

H represents clamping-plates or frames of substantially the same shape as and arranged on opposite sides of the field-plates of both the dynamo and motor. The field-plates, together with their clamping-plates, are firmly clamped together by horizontal rods or bolts I, located at opposite sides of 75 80 and parallel with the armature-shaft and which pass through holes in the sides of the field-plates and clamping-plates. The clamping bolts or rods I are of greatest diameter at their middle portions to form shoulders i, 85 against which the inner clamping-plates abut. The field and clamping plates are clamped between said shoulders and nuts i' screwed on threaded portions i" of the clamping bolts or rods outside of and adjacent to 90 the outer clamping-plates or frames. The reduced opposite end portions of the clamping bolts or rods pass through perforated lugs k on the bearing-standards, in which they are secured by nuts k', screwed on their 95 threaded ends. The field and clamping

plates are securely clamped on the rods or bolts 1 and are rigidly tied to the bearing-standards by the clamping rods or bolts, thus producing a very stable and strong 5 though light frame. The clamping-plates H are further secured to the base by bolts or screws l, which are inserted in registering holes in the base and flanges on the bottoms of the clamping-plates after the latter and 10 the field-plates have been clamped in place on the clamping bolts or rods.

M represents a switch the movable member m of which is moved in opposite directions to make and break contact with the 15 stationary members of the switch by a rod m', which is connected to the movable switch member and is reciprocated by the armature-shaft of the dynamo and motor through suitable gearing hereinafter described. This 20 switch, which is fully described in our application for United States Letters Patent, filed of even date herewith, Serial No. 202,374, is supported by a switch board or plate N, which rests upon the tops of the dynamo and 25 motor field-magnets and is secured to the upper ends of vertical columns or bolts n, which are screwed into threaded holes in the side portions of the bearing-standards for the armature-shaft or are otherwise secured 30 to the standards or base A. The switch board or plate is firmly and rigidly supported above the dynamo and motor and can be readily detached from the vertical supporting-bolts when necessary.

35 The reciprocating operating-rod m' for the switch is preferably connected by a link o to the upper end of a lever P, which is secured at its lower end to a rock-shaft p, journaled in bearing-lugs p' on the removable cap for 40 the bearing-standard E'. The rock-shaft has an arm p'', which extends down at one side of the bearing-standard and constitutes, in effect, a depending arm of the lever P.

45 Q is a crank-shaft which is journaled in the bearing-standard E' transversely of the armature-shaft and is provided at its outer end with a crank or wrist pin q, which works in an elongated slot in the depending arm of the operating-lever P for the switch. The 50 crank-shaft is driven from the armature-shaft by a worm-gearing consisting of a worm r, detachably secured to the adjacent end of the armature-shaft, and a worm-wheel r', secured to the crank-shaft and meshing with the worm. The crank-shaft preferably bears at one end in a bearing-hole r'' in one side of the bearing-standard E' and at its other end in a hole in a removable bearing-plate s, Fig. 4, which is preferably circular and is removably secured by screws or the like s' over a circular hole s'', Fig. 6, in the adjacent side of the bearing-standard, which hole is of larger diameter than the worm-wheel. By loosening and removing the bearing-plate s for the

crank-shaft the latter, with the worm-wheel 65 secured thereon, can be slipped endwise out of the bearing-standard, it being necessary only to lift the adjacent end of the armature-shaft sufficiently to permit the teeth of the worm-wheel to disengage the teeth of the 70 worm. The worm driving-gear for the switch is inclosed and protected in the hollow bearing-standard, and the latter provides 75 containing chambers for oil or grease for the worm-gearing and journal of the armature-shaft to run in. The removable caps for the bearing-standards are provided with lubricant-filling holes, closed by screw-plugs or other suitable closures t, which enable the introduction of lubricant into the lubricant-chambers without removing the bearing-caps.

U U' represent, respectively, the commutators, and u u' the brushes co-operating therewith, for the dynamo and motor. Each 85 pair of brushes is mounted on arms projecting from a supporting-ring u'', which surrounds a circular boss on the adjacent bearing-standard, to which it is secured by bolts or screws u'', Fig. 2, passing through holes in 90 arms on the supporting-ring. These features form no part of the present invention and are not herein described in detail.

The dynamo B is employed, as in said patented system, as fully explained in the patent, to excite the field-winding of the main generator and is driven by the motor B', and the switch is used, as fully explained in said application Serial No. 202,374, for regulating the voltage of the work-circuit by successively introducing counter-electromotive-force cells or other resistance into and withdrawing the same from the system.

We claim as our invention—

1. The combination with an electric dynamo and a motor comprising parallel field-magnets, and rotary armatures mounted on a common shaft, of a base on which said field-magnets are secured, bearing-standards at the opposite ends of said base in which the 105 ends of said armature-shaft are journaled, and rods at opposite sides of said field-magnets detachably secured at their ends to said bearing-standards and removably secured between their ends to said field-magnets to hold 110 the latter rigidly in place, substantially as set forth.

2. The combination with an electric dynamo and a motor comprising parallel field-magnets, and armatures mounted on a common shaft, of a base on which said field-magnets are removably secured, bearing-standards at the opposite ends of said base in which the ends of said armature-shaft are journaled, removable caps for said bearing-standards, 120 and rods at the opposite sides of said field-magnets detachably secured at their ends to said bearing-standards and removably se-

cured between their ends to said field-magnets to hold the latter rigidly, substantially as set forth.

3. The combination with an electric dynamo and a motor having field-magnets comprising thin plates, and rotary armatures mounted on a common shaft, of a base, bearing-standards at the opposite ends of said base in which the ends of said armature, shaft are journaled, clamping-rod secured at their ends to said standards and passing through holes in said field-plates, said clamping-rod having shoulders and screw-threaded portions at opposite sides of said field-plates, and nuts screwed on said threaded portions of the rods for clamping said field-plates together, substantially as set forth.

4. The combination with an electric dynamo, and a motor comprising parallel field-magnets, and armatures mounted on a common shaft, of a base on which said field-magnets are secured, bearing-standards at the opposite ends of said base on which the ends of said armature-shaft are journaled, rods at the opposite sides of said field-magnets detachably secured at their ends to said bearing-standards and detachably secured between their ends to said field-magnets to hold the latter rigidly in place, a switch, and a board therefor arranged over said dynamo and motor and removably secured to supports secured to said base, substantially as set forth.

5. The combination with an electric dynamo and a motor comprising parallel field-magnets, and armatures mounted on a com-

mon shaft, of a base to which said field-magnets are secured, bearing-standards at the opposite ends of said base on which the ends of said armature-shaft are journaled, rods at the opposite sides of said field-magnets secured at their ends to said bearing-standards and between their ends to said field-magnets to hold the latter rigidly in place, a switch, a board therefor arranged parallel with and secured to said base, and gearing connecting said switch and armature-shaft, substantially as set forth.

6. The combination with an electric dynamo and a motor comprising parallel field-magnets, and armatures mounted on a common shaft, of a base on which said field-magnets are secured, bearing-standards at the opposite ends of said base in which the ends of said armature-shaft are journaled, removable caps for said bearing-standards, a switch-board removably mounted above said dynamo and motor, a switch carried by said board, one of said bearing-standards being hollow, operating-gearing for said switch enclosed by said hollow bearing-standard, and a side plate for said hollow bearing-standard which is removable with one of said gears enclosed by said standards, substantially as set forth.

Witness our hands this 26th day of March, 1904.
